UNITED STATES PATENT OFFICE.

BENJAMIN C. GOCHENOUR, DECEASED, LATE OF SPOKANE, WASHINGTON, BY ALICE GOCHENOUR, EXECUTRIX, OF SPOKANE, WASHINGTON.

FURNACE.

Application filed June 11, 1924. Serial No. 719,338.

To all whom it may concern:

Be it known that I, ALICE GOCHENOUR, executrix of the estate of BENJAMIN C. GOCHENOUR, deceased, a citizen of the 5 United States, residing at East 113 Baldwin Avenue, Spokane, in the county of Spokane and State of Washington, hereby submit an invention of BENJAMIN C. GOCHENOUR, deceased, who during his lifetime invented 10 certain new and useful Improvements in Furnaces, of which the following is a specification, reference being made therein to the accompanying drawing.

This invention relates to improvements in 15 furnaces pertaining more particularly to an ore reduction furnace in which an oil blast burner is utilized as the heating element.

One of the objects of the invention is to provide an improvement in a furnace for 20 reducing crude ores.

Another object of the invention is to provide a furnace constructed in a manner whereby it can expand without injury to itself.

25 Another and further object of the invention is to provide a novel manner of heating the air and oil supply to the furnace burner.

A still further object of the invention is to provide a novel form of seepage pan for 30 receiving and conveying the molten metals which are recovered from the ore.

A further object of the invention is to so construct the furnace that there is a continuous flow of slag from the furnace oven.

35 Another and further object of the invention is to provide means for collecting the fumes generated from the ore in the furnace oven.

Other further objects, improved points of 40 construction and novel results of the invention will appear in the following description and accompanying drawing.

In the drawing:

The figure is a view of the furnace together with its cooperating parts, the furnace proper being shown in vertical section.

Throughout the description of the invention like numerals designate similar parts 5 representing the furnace base and 6 the outer walls of the furnace.

The base and outer walls are preferably concrete although other material can be substituted if desired. The oven walls proper are designated at 7 and are preferably brick, 55 the inner-most surface of the walls being a

magnesite brick to better withstand the intense heat in the oven. Between the oven walls 7 and the outer furnace concrete walls 6 there is provided a dry clay filling 8 which forms an expansion cushion between the 60 inner and outer walls. The concrete walls 6 of the furnace are provided with vertical reinforcing rods 9 while horizontal reinforcement of these walls is provided by the hollow pipes 10.

Suitably supported above the base 5 of the furnace and in the bottom of the furnace oven 11 is a seepage pan 12 made of suitable metal. The front end 13 of the pan is elevated while the opposite or rear end of the 70 pan 14 is in a lower horizontal plane and extends outwardly through the opening 15 in the concrete wall 6 terminating in a well 16. The seepage pan extends the entire length and depth of the oven and slants 75 slightly towards the rear of the oven as before mentioned. The seepage pan is adapted to receive bricks 17 which are loosely laid in the pan and so arranged therein as to provide a series of steps 18 80 between the front and rear ends of the pan. The upper layer of the bricks in the pan are magnesite bricks because of their contact with the intense heat of the oven and as readily appears in the drawings these bricks 85 assume the gradual slant towards the rear of the oven and in reality constitute the oven bottom. The ore is deposited in the oven upon the long, front step 19 of the brick oven bottom.

The oven is closed by a suitable brick top 20 the inner face of which is made of magnesite brick. Extending transverse the oven top 20 are upwardly extending walls 21 which form between them a bin 22. The 95 bin 22 is adapted to receive the ore 23 prior to its delivery to the furnace and the ore is of course subjected to a large degree to the oven heat while in this bin and therefore becomes thoroughly dry before it is delivered into the oven. The ore can be delivered in any convenient way to the step 19 of the oven bottom as for instance through the opening 24 through the oven top.

Suitably supported in the oven 11 and 105 extending lengthwise thereof above the oven bottom is a horizontal flue 25 having an opening 26 in its rear end while the front end 27 of the flue joins the vertical flue 28. The lower end 29 of this vertical flue is 110

- open and positioned above the step 19 of the oven bottom, the flue extending upwardly through the top of the oven and the front wall of the bin 22, its upper end 30 being in communication with a settling or fume collecting tank or chamber 31. Positioned above the horizontal flue 25 and extending slightly upward towards the rear of the oven is a flue 32. One end of this flue is in communication with the vertical flue 28 while at 33 midway the length of the flue it joins flue 34 and from this point flue 34 extends vertically upward through the oven top and the rear wall of the bin 22. The upper end 35 of this flue communicates with the fume collecting chamber 31. Adjacent the connection of the two vertical flues with the fume collecting chamber these flues are provided with adjustable dampers 36.
- 20 The fume collecting tank or chamber may be of any desired shape or size to meet the existing conditions. The chamber has closed ends and is provided with interior screens or baffle plates 37. One end wall of the chamber is provided adjacent the chamber bottom with a door 38 through which the collected or settled substance taken from the ore fumes can be removed from the chamber. The settling chamber 31 is further provided with an outlet pipe 39 which is in communication with a stack 40. The stack 40 above its communication with the pipe 39 can be provided with a water spray 41. The purpose of this spray will be hereinafter described and its use is optional.
- 25 The rear wall of the furnace is provided with an opening 42 the inner end of which is on a line with the rear end of the bricks in the seepage pan 12. This opening is for the purpose of allowing the slag which moves along the oven bottom and over the steps therein to escape from the oven. The opening is provided with a chute 43 at its end. This opening and chute are positioned low enough that when the ore slag starts flowing over the oven bottom a continuous flow of slag is moving at all times through the opening and over the oven floor.
- 30 The rear furnace wall is further provided with openings 44 and 45 which are normally closed. These openings give access to the oven for the purpose of repairing or cleaning the oven and flues.
- 35 The oven 11 is heated by an oil blast burner 90 which extends through the front furnace and oven walls to a point just above the oven floor step 19. The oil for the burner 45 is supplied from the tank 46 by means of a pipe 47 which extends through the second horizontal reinforcing pipe 10 and down the back of the furnace as at 48 into the fourth hollow reinforcing pipe 10 and out to the front of the furnace at 49 where there is provided a valve con-

trol 50. Because of the oil pipe line being carried through these hollow pipes the oil is delivered to the burner 90 preheated, once the furnace is in operation.

There is provided a suitable air pump 51 which delivers air to an air supply tank 52 from which it is carried by the pipe 53 through the upper hollow reinforcing pipe 10 and down the back of the furnace as at 54 and through the third horizontal pipe 10 out to the front of the furnace at 55 where a suitable control valve 56 is provided. From this it will be seen that the air is also preheated before delivery to the burner 45.

The air and pipe lines meet at 57 and deliver an air and oil mixture to the burner 90 through a common pipe 58.

Operation.

From the foregoing it will be seen that in the operation of the furnace the dried and somewhat heated ore in the bin 22 is allowed to deposit upon the step 19 of the oven bottom. The burner 90 is then started, the force of the air supplied to the burner being sufficient to blend the oil and air into a fine spray which comes in contact with the heated oven. It will of course be readily understood that the oven is heated in some suitable or long practiced manner prior to the starting of the oil spray burner 45.

The heat immediately begins to work upon the ore causing it to disintegrate and start to flow or move down the steps 18 of the oven bottom. In a short time a continuous flow of slag is moving over the length of the bottom and out of the slag opening 42 and over the slag chute 43. The different metals contained by the ore will of course become molten and will seep down between the loosely placed bricks 17 in the seepage pan. This molten metal will eventually reach the seepage pan and flow down its length and be collected in the well 16 at the end of the pan.

In the meantime the fumes from the ore have been thrown off and these find escape through the horizontal flues 25 and 32 and the vertical flues 28 and 34. These fumes will pass up the escape flues which are of a size to take care of them without need of additional force other than the explosion of the heated oil sprayed into the oven.

Upon reaching the settling tank or fume collector 31 the fumes come in contact with the screens or baffles 37 where the heavier fumes or dust are collected allowing the remaining fumes to pass from the tank through the pipe 39 into the stack 40. This stack 40 is not built high enough to create any appreciable amount of draft but is used only to allow the escapement of the residue of fumes from the settling tank.

As before mentioned a water spray 41 can be used in this stack if desired so as to

further cause a settlement of whatever heavier elements or dust may be contained by the fumes which eventually reach the stack. Any settlement which takes place because of the water spray can be collected by any common suitable construction at the bottom of the stack.

Attention is directed to the fact that the settling tank or fume collector is large enough and long enough to allow the fumes to ripen and settle and that both the inlet and outlet pipes of the collector are controlled by dampers to control the draft through the collector.

The metals which find their way to the well 16 will of course depend upon the character of the ore operated upon. The deposit in the fume collector will also be controlled by the character of the ore operated upon. The deposit in the fume collecting chamber can be removed through the door 38 and if desired this deposit can be separated into its several different elements. It has been found however that without separation the deposit in the fume collector can be mixed with linseed oil with the result that a very good mixed paint will be had.

It will be readily seen that the fumes which rise from the ore in the oven can enter the horizontal flue 28 at the rear end of the oven, but it will also be seen, in the event these fumes are not ripe or light, that when they reach the vertical flue 28, the heavier or unripened fumes will be drawn downward through the open lower end 29 of the vertical flue, and again enter the oven where they will be reheated and ripened so that they can escape to the fume collector.

Having thus described my invention, what I claim and desire to secure by Letters Patent is:

1. In an ore reduction furnace or the like, an oven, a heater for the oven, a seepage pan beneath the oven bottom, and communication between the oven bottom and the seepage pan, for the purpose described.

2. In an ore reduction furnace or the like, an oven, a heater for the oven, horizontal and vertical flues in communication with the oven, a fume collector in communication with the flues, and a seepage pan beneath the oven bottom, for the purpose described.

3. In an ore reduction furnace or the like, an oven, adapted to receive ore or the like, a vertical flue in communication with the front end of the oven, a horizontal flue above the oven, one end of the horizontal flue in communication with the rear end of the oven and its opposite end in communication with

the vertical flue adjacent the lower end thereof, whereby the heavy fumes entering the horizontal flue from the rear end of the oven are drawn back into the oven through the lower end of the vertical flue to be reheated and ripened.

4. In an ore reduction furnace or the like, an oven, a burner for the oven, an inclined oven bottom provided with steps, and an opening in the rear of the oven whereby the material in the oven progresses the length of the oven bottom in the manner described.

5. In an ore reduction furnace or the like, an oven, a burner for the oven, a horizontal flue above the oven, a vertical flue in communication with the front end of the oven, one end of the horizontal flue in communication with the rear end of the oven and its other end in communication with the vertical flue adjacent its lower end, the vertical flue in communication with a fume collector, a chimney, communication between the chimney and the fume collector, and adjustable drafts between the chimney and the fume collector, and the fume collector and the oven, for the purpose described.

6. In an ore reduction furnace or the like, an oven, a bottom for the oven composed of loosely laid bricks supported in a seepage pan, and the seepage pan extending through the rear wall of the oven and terminating in a well, whereby the metals in the ore in their molten state are delivered to the seepage pan well.

7. An ore reduction furnace or the like, an oven, an oven bottom composed of loosely laid bricks supported by a seepage pan extending throughout the length and breadth of the oven and having its rear end extending through the rear end of the oven wall, the outer end of the seepage pan terminating in a well, the front end of the oven bottom adapted to receive ore or the like, the oven bottom inclined towards the rear of the oven and provided with a series of steps, the rear step of the oven in communication with an opening through the rear oven wall, a chute in said opening, whereby when the furnace is in operation the metal melted from the ore finds its way through the oven bottom to the seepage pan and its well and the ore slag progresses the length of the oven bottom and is discharged from the end of the chute in the rear oven wall opening.

In testimony whereof I hereunto affix my signature.

ALICE GOCHENOUR,
Executrix of the Estate of Benjamin C. Gochenour, Deceased.
